Primary Examiner—Jennifer Rivard

(74) Attorney, Agent, or Firm—The Halvorson Law Firm

(73) Assignee: **The Christmas Light Company Inc.**,
Mesa, AZ (US)

(57) **CLAIM**

(**) Term: **14 Years**

The ornamental design for a safety cage for electrical plugs,
as shown and described.

(21) Appl. No.: **29/170,986**

DESCRIPTION

(22) Filed: **Nov. 14, 2002**

FIG. 1 is a perspective view of the present invention;

(51) LOC (7) Cl. **13-03**

FIG. 2 is a top plan view of the present invention;

(52) U.S. Cl. **D13/156**

FIG. 3 is a left side elevation view of the present invention;

(58) Field of Search **D13/154-156;**

FIG. 4 is a right side elevation view of the present invention;

439/367, 369

FIG. 5 is a bottom plan view of the present invention;

(56) **References Cited**

FIG. 6 is a front elevation view of the present invention;

U.S. PATENT DOCUMENTS

FIG. 7 is a rear elevation view of the present invention; and,

5,913,692 A * 6/1999 Targett 439/369
